UNITED STATES PATENT OFFICE.

MANUEL PAZOS, OF BARCELONA, SPAIN.

EXPLOSION-ENGINE.

1,147,640.

Specification of Letters Patent. Patented July 20, 1915.

Application filed September 22, 1913. Serial No. 791,159.

To all whom it may concern:

Be it known that I, MANUEL PAZOS, a subject of the King of Spain, residing at Girona street 37, Barcelona, Spain, have invented certain new and useful Improvements in Explosion-Engines; and I do hereby declare the following to be a full, clear, and exact description of the invention, such as will enable others skilled in the art to which it appertains to make and use the same.

My invention relates to explosion engines and consists in the construction and arrangement of parts as set forth in the annexed specification.

15 One object of my invention is to provide an improved rotary valve, adapted to control the cycles of two adjacent cylinders of the engine.

A further object of my invention is to 20 provide novel means for actuating these valves and other auxiliary devices so arranged that the valves and actuating means therefor are readily removed from the rest of the engine and all the parts easily accessible.

In the accompanying drawings, representing an embodiment of my invention, Figure 1 is a side elevation, partly in section, of my improved engine, Fig. 2 is a horizontal section in line II—II of Fig. 1, Figs. 3, 4 and 30 5 are views of the rotary valves in several positions, partly in section, Fig. 6 is a perspective of a rotary valve, parts being broken away, Fig. 7 is a perspective of same, 35 parts being broken away along lines VIII—VIII and VII—VII of Fig. 6, Fig. 8 is a longitudinal section through the valve, in plane of lines VIII—VIII of Fig. 6, Fig. 9 is a diagrammatic view of a valve taken 40 along lines 9—9 of Fig. 7, in direction of arrows, and Fig. 10 is a similar view along lines 10—10 of Fig. 7, in direction of arrows.

Each rotary valve controls two cylinders of the engine; in Fig. 1 two rotary valves are shown, as applied to a 4 cylinder, 45 4 cycle engine.

1, 2, 3 and 4 represent the 4 cylinders; cylinders 1 and 2 are controlled by rotary valve 5, and cylinders 3 and 4 by rotary valve 6, the valves located with respect to the cylinders as shown in Fig. 2, being symmetrically between them and to one side. The valve communicates with the cylinders through 55 suitable openings in the side of the cylinder,

that periodically register with openings in the conical surfaces of the valves.

Exteriorly, a rotary valve is shaped like two truncated cones set base to base; the valve is constructed to control cylinders of 60 the 4 cycle type. Formed integrally with the valves is the cylindrical part 9, which is divided into 2 chambers 11 and 12 by partition 10; said partition is provided with a hole 53 for reception of the member 14 on 65 which the valve is mounted.

Radiating outwardly and longitudinally from the cylindrical part 9 are 4 partitions p' , p^2 , p^3 , and p^4 , which alone would form 4 longitudinal chambers just outside the cyl- 70 inter 9. The partition 10, however, which is at right angles to said radial partitions, is extended across two opposite chambers, forming 4 small chambers, namely A' and C' on one side and A² and C² on the other;

the other two large chambers, B and D, extend the whole length of the valve. Chamber A' communicates with the longitudinal chamber D through the opening d' , cut through the radial partition. This chamber 75

further communicates with the cylinder 1, by means of a port a' , cut through the exterior wall of the valve, registering with the opening 39 in the side of the cylinder 1. Longitudinal chamber B communicates with 80 chamber 11 by means of the opening e' , and with the cylinder 1 by the port b' , cut through the exterior wall of the valve, regis- 85

tering with the opening 39. On the other side of the valve, analogous ports a^2 and d^2 are provided for communication with the cylinder. Chamber A² communicates with 90 longitudinal chamber B through the opening b^2 . Chamber D communicates with chamber 12 by the opening e^2 . The valve 95 is inclosed within a casing 38.

The size of the various openings shown may be varied to suit practical working conditions, the drawings showing merely the structure and relationship between the various parts. 100 Chamber 11 of the valve leads directly to the exhaust 28, while chamber 12 on the other side, is connected directly to the charge intake pipe 26, connected to carburetor 25. For the other valve, 6, the right hand side 105 of the valve communicates with the intake pipe 27 from the carburetor, and the other side with the exhaust 29. The structures of the valves are precisely similar.

The valve operates as follows (see Figs. 9 and 10): In the position shown in Fig. 9, the suction from the cylinder creates a partial vacuum in chamber A', which acts, 5 through opening d', to create a partial vacuum in chamber D; this sucks a charge from chamber 12, which passes through opening e², along chamber D, through opening d', into chamber A', through port a', 10 and thence into the cylinder.

Simultaneously with the above, cylinder 2 is exhausting, the path of the gases being as follows: port a², chamber A², opening b², chamber B to the exhaust side of the valve, 15 through opening e', into chamber 11 and thence to the exhaust pipe 28. On the next cycle, cylinder 1 is at compression; cylinder 2 sucks in a charge from chamber 12 through opening e², into chamber D, through port d², 20 and thence to the cylinder. On the following cycle, cylinder 1 is at explosion, and cylinder 2 at compression. On the fourth cycle, cylinder 1 exhausts, the gases passing through port b', into chamber B, through 25 opening e', into chamber 11 and thence to exhaust pipe 28. Meanwhile cylinder 2 is at explosion.

In Fig. 2, the cylinders 1, 2, 3 and 4 are respectively at suction, exhaust, compression 30 and explosion; in Fig. 3, at compression, suction explosion and exhaust; in Fig. 4, at explosion, compression, exhaust and suction; in Fig. 5, at exhaust, explosion, suction and compression.

35 The valves are mounted on shafts 14, which terminate in heads 37 engaging with sockets 40 carried at opposite ends of shaft 15. It is evident that rotary motion of the shaft 15 will rotate the valves 5 and 6, and 40 that the head 37 is readily disengaged from the socket 40. The whole valve is then readily removable, upon detaching the upper half of the casing 38. The shaft 15, through the pulley 16 mounted thereon, and 45 the shaft 20, through the pulley 19 mounted thereon, are operated by a belt 17 that passes over said pulleys and that receives its power from the pulley 18 mounted on the shaft 24. Shaft 24, carrying pulley 23, is 50 operated by a belt 30; belt 30 is operated by the pulley 33, that is clamped between the disks 31 and 32. The crank shaft 34 of the engine is made in two sections, that terminate in disks 31 and 32, clamped together by 55 bolts 31^a. At opposite ends of shaft 20 are heads similar to those on shaft 15, that engage with the operating shafts of a circulating pump 21 and magneto 22.

The transmission mechanism is all mounted 60 in the casing 35, which is secured to the

frame 41 of the engine by bolts 36. By removing these bolts 36, the whole casing 35 is readily removable, for repairs, cleaning or adjustment of parts.

The simple and strong construction of the 65 rotary valve, its being easily removable for cleaning or repairs, its positive actuation from the crank shaft, and the inclosure of the valve, pump and magneto operating means in a readily removable casing, all result in an improved and desirable engine. 70

I claim—

1. A rotary valve for 4 cycle engines, adapted to control two cylinders thereof, comprising two central chambers connected 75 to the charge forming means and exhaust, respectively, an outer member and radiating transverse partitions carrying suitable passages for controlling the paths of the gases through the valves and cylinders. 80

2. A rotary valve for 4 cycle engines, adapted to control two cylinders thereof, comprising two central chambers, connected to the charge forming means and exhaust, respectively longitudinal partitions radiating therefrom, a transverse partition, and an outer member carrying ports for registering with the cylinder ports, said members carrying openings at suitable points for controlling the path of the gases. 90

3. A rotary valve for four-cycle engines, adapted to control two cylinders thereof, comprising a central member forming two chambers connected to the charge forming means and exhaust respectively, an outer member shaped like two truncated cones, vanes radiating from said central member to the outer member, a transverse partition, the outer member carrying ports adapted to register with ports in the cylinders and the inner members provided with openings to permit suitable passage of gas. 95 100

4. A rotary valve for four-cycle engines, adapted to control two cylinders thereof, comprising two central chambers, connected 105 respectively to the charge forming means and exhaust, two longitudinal adjacent outlying chambers opening into said central chambers, vanes radiating from said central chambers, a transverse partition forming smaller chambers, and an outer member carrying inlet and exhaust ports, said vanes and said smaller chambers carrying openings at suitable points. 110

In testimony whereof, I affix my signature, in presence of two witnesses.

MANUEL PAZOS.
